GUSTAV F. RICHTER, OF BROOKLYN, NEW YORK.

TONSIL-REMOVER.

1,375,177.

Specification of Letters Patent. Patented Apr. 19, 1921.

Application filed April 15, 1919. Serial No. 290,144.

To all whom it may concern:

Be it known that I, GUSTAV F. RICHTER, a United States citizen, residing in Brooklyn, New York, have invented the following described Improvements in Tonsil-Removers.

The invention concerns tonsil removers of that class in which the severing members are relatively dull and function by pinching or crushing the tissue along the line of severance rather than by cutting or shearing. Considerably greater power is required to sever the tonsil in this way than is necessary for the shearing process which makes a power multiplying device essential but the severing members must also have the same length of stroke as in the ordinary tonsillotome. It involves considerable mechanical complication to provide adequately 10 forceful power means giving a sufficiently long stroke and ordinary power multiplying means, if employed for this purpose, are found to be slow and clumsy in operation and to obstruct vision of the work. The present invention provides a means for removing tonsils by crushing in which the closing movement is effected in two stages. The first serves to advance the blade member into the tonsil tissue without cutting it and to such extent as to condense and firmly 20 compress the tissue along the intended line of severance. The second stage serves to complete the closing movement of said member, crushing off the tonsil and involves the application of the power multiplying means which is thus only employed to make the short final stroke, the only part which requires great power and the operation of this means is properly safe-guarded so that 30 it can only become active after the initial closing movement has been accomplished and the tonsil firmly compressed. The improvements are illustrated in the accompanying drawing which illustrates the form 40 of the invention at present preferred and which will suffice to indicate the principle involved and indicate other means by which the same principle may be used with equal effect.

50 In said drawing—

Figure 1 is a side elevation of the instrument with the severing members in their fully opened position;

Fig. 2 a top plan showing the severing members in the position occupied at the end of the first stage of closing movement;

Fig. 3 a longitudinal, enlarged section of Fig. 2 with the power multiplying means about to act; and

Fig. 4 is a detailed section of the lock.

The severing members are marked 1 and 2 of which 1 may be regarded as a blade and 2 the bed with which it coöperates and which in the present case consists of a semi-circular bar with a groove along its inner circumference to receive the blunt edge of the blade. The bed member 2 is carried on the end of a frame shank 3 and the blade member 1 is similarly carried on the end of a blade shank 4 superposed upon shank 3 and appropriately confined thereon for longitudinal reciprocation. The confining means consists in the present case of the parallel extremities of the bed groove identified at 5 in Fig. 2 and forming a guideway to receive the enlarged end of the blade shank or the blade itself. The outer end of the blade shank is further confined by a stud 6 on the frame shank projecting through a slot 7 in the blade shank and connected to a stiff spring 8 overlying said shank. The spring 8 is connected to the post by a bayonet joint connection as indicated in Fig. 3 so that it can be removed when necessary and the slot 7 is of sufficient length to permit the blade 85 to be withdrawn from the guideway 5 and then lifted off of the post and the frame shank. A small projection 9 on the under face of spring 8 is adapted to occupy the slot 7 when the spring is in place and serves 90 as an abutment limiting the opening movement of the blade and also serves as a retainer for the bayonet joint which is so constructed that it cannot be unlocked until the spring has been turned at right angles 95 to the shanks. Thus the operation of removing the blade shank from the frame of the instrument consists merely in lifting the projection 9 out of the slot 7, turning the spring 8 to a transverse position, then 100 pushing it endwise until the head of stud 6 can be passed through the large part of the bayonet slot and then withdrawing the blade from the guideway 5 and from the frame. It will be plain to persons skilled in the surgical instrument art that various other means of removably confining the two blade members in operative relation may be used in place of that above described and with the same effect.

When the blade member has been moved outwardly until the inner end of the slot 7

abuts against the stop pin 9 on the spring the severing members are in their opened position and ready to be placed so that the tonsil to be severed projects between them. 5 The outer end of the blade member carries a thumb piece 10 and the outer end of the frame shank 3 is equipped with a grip 11 extending substantially at right angles thereto and in such position that when in 10 the operator's hand, the thumb can be used for forcing the thumb-piece 10 and blade toward the tonsil, forcing the blade 1 toward its bed 2, thus producing the initial closing movement of the severing members. 15 The coöperating grip member 12 is a lever fulcrumed in the frame at 13 and having a short arm provided with a cam surface 14 and adapted to enter a slot 15 in the blade shank 4 engaging with the inner end of 20 said slot. The cam surface 14 is so related to the end of the slot 15 that the closing of the grip members 11 and 12 will exert a powerful endwise thrust on the blade shank 4 and thereby drive the blade 1 toward and 25 into the groove of its bed 2 thus completing the second and final stroke of the closing movement. It will be obvious that the power multiplying means represented by the levers 12 and 11 cannot engage upon the 30 blade shank 4 until the latter has been closed sufficiently to bring the slot 15 into registry with the short arm of lever 12. This position of the slot will ordinarily be observed by the operator but for the purpose of preventing premature use of the 35 power means a lock is provided for the latter and arranged to be automatically released by the blade shank when its notch 15 has reached a position to be engaged by the 40 cam surface 14. Locking means for this purpose may be variously constructed. That herein illustrated consists of a spring blade 16 mounted on the side of the grip lever 11 and carrying a hardened steel locking lug 17 which enters a hole in the frame shank 3 and is adapted to enter a similar 45 hole 18 in the grip lever 12 when the two levers are in their most widely separated position and thus lock said grip lever 50 against operation. The upper end of the spring 16 projects alongside the blade shank 4 in a position in which it is adapted to be engaged by a cam 19 on the side of latter as indicated in Fig. 2. The cam 19 is so 55 located that it engages and forces the spring 16 and its locking stud 17 laterally and out of engagement with the lever hole 18 when the blade members have completed their initial closing movement. The grip members 60 may then be operated to perform the second stage of the closing process but cannot be operated prematurely. Being held against closing during the initial stage the grip levers 11 and 12 constitute a very satisfactory handle for the device as a whole 65

permitting the free manipulation by the thumb or finger of the thumb piece 10.

It will now be apparent that the principle of this invention, comprising an organization of elements permitting a two-stage 70 closing of the blade members, can be embodied in different forms of apparatus and can utilize different kinds of power multiplying means for producing great pressure in the second stage and that various modifications, substitutions, additions and subtractions may be resorted to without departing from the said principle. 75

This application contains matter disclosed and claimed in my former application Serial 80 No. 215,991, filed February 11, 1918.

Claims:

1. A tonsil remover comprising a bed and blade guided therein adapted to close on the tonsil and a two-stage closing means 85 therefor comprising a thumb - or - finger-operated member for intially closing the bed and blade on the tonsil to compress the same and levers to be gripped within the hand for completing the closing movement. 90

2. A tonsil remover comprising overlying relatively reciprocating shanks, one carrying a blade and the other a bed therefor and adapted to be closed on the tonsil and a two-stage closing means therefor comprising a thumb-push and a pair of grip levers connected substantially at right angles to said shanks, and means for predetermining the successive operation of said means. 95

3. A tonsil remover comprising a bed and 100 blade adapted to be closed on the tonsil, two members for closing the same, and means for locking one member until the other has been operated.

4. A tonsil remover comprising bed and 105 blade members adapted to be closed on the tonsil, a hand grip on one of said members, a thumb-push on the other and a grip lever for applying power to the last named member, and means for predetermining the 110 sequence of operation of said push and lever.

5. A tonsil remover comprising bed and 115 blade members adapted to be closed on the tonsil, two closing members therefor, a lock normally locking one of said members and means associated with the other member adapted to release the lock.

6. A tonsil remover comprising a bed, a coöperating blade, the two being adapted to close on the tonsil, and a two stage closing means therefor comprising a member operable by a movement of a finger toward the tonsil, for initially closing the bed and blade on the tonsil, and power multiplying means for completing the closing movement. 120

7. A tonsil remover comprising severing members consisting of a bed and a blade adapted to close on the tonsil, and a two stage closing means therefor comprising a part connected to each of said severing mem- 125

bers engageable by the operator's hand and thereunder coöperating to initially close said severing members, and a lever simultaneously engageable by the same hand for completing the closure thereof.

8. A tonsil remover comprising severing members consisting of a bed and a blade adapted to close on the tonsil, and a two stage closing means therefor comprising a part connected to one of said severing members and a slidable member connected to the

other of said severing members, said part and slidable members being arranged to be coöperatively engaged by the operator's hand to initially close said bed and blade, 15 and a grip lever adjacent said slidable member, to be gripped within the hand for completing the closing movement.

In testimony whereof, I have signed this specification.

GUSTAV F. RICHTER.
